Assistant Examiner — Christina Gabrielle Cosden

(57) **CLAIM**

The ornamental design for a children's refrigerator lock, as shown and described.

DESCRIPTION

FIG. 1 is a front perspective view of a children's refrigerator lock showing my new design.

FIG. 2 is a rear perspective view thereof.

FIG. 3 is a bottom view thereof.

FIG. 4 is a top view thereof.

FIG. 5 is a left side view thereof.

FIG. 6 is a right side view thereof.

FIG. 7 is a front view thereof; and,

FIG. 8 is a rear view thereof.

The broken lines shown in FIGS. 1 and 7 are for purposes of illustrating portions of the children's refrigerator lock that forms no part of the claimed design.

1 Claim, 8 Drawing Sheets
